UNITED STATES PATENT OFFICE.

FRANK CROSS, OF ST. LOUIS, MISSOURI, ASSIGNOR OF ONE-HALF TO THOMAS M. HOBBS, OF CARMI, ILLINOIS.

TEMPLLET.

Application filed February 19, 1927. Serial No. 169,591.

This invention relates to geometrical instruments and its general object is to provide a stair and building templet that is capable of being extremely easily and quickly applied for getting accurate measurements between two given points so that accurate cuts can be obtained by said measurements with the result that when my novel templet is used, the work of building stairs, shelves or anything that requires accurate measurements will be simplified and can be easily done in an efficient and expeditious manner and with exactness and precision.

A further object of the invention is to provide a templet that is extremely simple in construction, strong and sturdy and inexpensive to manufacture.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a top plan view of the templet forming the subject matter of the present invention.

Figure 2 is an edge elevation thereof.

Figure 3 is a fragmentary top plan view with the parts extended.

Figure 4 is a fragmentary sectional view taken on line 4-4 of Figure 1.

Figure 5 is a sectional view taken on line 5-5 of Figure 3.

Figure 6 is a sectional view taken on line 6-6 of Figure 4.

Figure 7 illustrates one of the uses of my templet and showing the same positioned between shelf uprights.

Figure 8 shows a templet applied to a board that has been scribed to be cut, and secured between the uprights shown in Figure 7.

Referring to the drawings in detail the reference numerals 1 and 2 indicate cooperatively associated overlapped elongated body strips having enlarged rounded apertured ends 3 and 4 each of which is provided with a squared inner end 5 to accommodate the adjacent end of the companion strip when

the said strips are normally disposed as shown in Figures 1 and 2 of the drawings. The strip 1 is provided with a longitudinal slot 6 extending from its center toward one end and terminating adjacent said end while the strip 2 is provided with a similar slot 7 extending from its center toward its end opposite the termination of the slot 6. Secured in the inner ends of these slots 6 and 7 is what I term a center bolt 8 having a head 9 counter-sunk in the strip 2 and a knurled nut is threadedly secured to the bolt whereby the strips can be held at any given length it being apparent that the slots provide for the sliding movement of the strips on the bolt 8. The strips are further provided with tongues 10 and 11 respectively extending outwardly from the center bolt opening and received in grooves 12 and 13 for slidable movement so that a strong and sturdy structure is provided and the strips will be properly braced when arranged in open position as suggested in Figure 3 and shown in Figures 7 and 8.

Arranged in the apertures of the enlarged ends 3 and 4 are headed end bolts 14 and 15 which like the center bolt are provided with knurled nuts 16 and washers 17. Disposed between the washers 17 of the end bolts and the ends 3 and 4 of the strips, are the enlarged ends of blades 18 of like shape as shown in Figure 1. These blades 18 are tapered toward their free ends and are mounted for pivotal movement on the bolts 14 and 15 whereby they can be swung at various angles with respect to the strips 1 and 2 or in alignment therewith or in parallelism therewith as shown in Figures 1 and 2 and of course the nuts 16 are to be tightened to retain the blades in any desired position. The strip 2 is provided on its inner surface with graduations 19 and numerals 20 to indicate inches as shown in Figure 3.

From the above description and disclosure in the drawings, it will be obvious that I have provided a templet that can be used efficiently in the building of stairs, shelving and like work where accurate measurements are necessary and by the use of my novel templet the finished work will be neat and perfectly fitted, done in an expeditious manner and with very little effort on the part of the builder. While I have shown my templet in Figures 7 and 8 of the drawings, in use in the building of shelves, the templet

can also be used successfully and advantageously in the building of stairs and other work as above set forth.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

A templet of the character described comprising a pair of tongue and grooved body strips superimposed and slotted longitudinally from their center in a manner whereby the slots extend in opposed directions with respect to each other with their outer ends terminating adjacent one end of the 20 strips, said body strips having their tongues

arranged in their grooves for slidable movement whereby said strips are mounted for longitudinal movement with respect to each other, a headed bolt normally disposed in the inner ends of said slots and passing therethrough with its head countersunk in one of said strips, a nut on said bolt and adapted for retaining said strips at various positions with respect to each other, apertured heads formed with said strips, a bolt 25 passing through the apertures of said heads, tapered blades having their wider ends pivotally mounted on said bolts, and nuts on the bolts last mentioned for securing said blades at predetermined positions with respect to said strips and each other respectively.

In testimony whereof I affix my signature.

FRANK CROSS.
